[57] CLAIM

The ornamental design for a shoe sole, as shown and described.

DESCRIPTION

FIG. 1 is a bottom plan view of a shoe sole showing our new design, the top, not shown, being flat, plain and unornamented;

FIG. 2 is a right side elevational view thereof, the left side being a mirror image thereof;

FIG. 3 is a cross-sectional view as taken from line 3—3 of FIG. 1;

FIG. 4 is a cross-sectional view as taken from line 4—4 of FIG. 1;

FIG. 5 is a cross-sectional view as taken from line 5—5 of FIG. 1;

FIG. 6 is a partial cross-sectional view of the heel portion as taken from line 6—6 of FIG. 1.
